UNITED STATES PATENT OFFICE.

GEORGE E. HARDESTY, OF FOLSOM, NEW MEXICO.

FARM-GATE.

1,361,152.

Specification of Letters Patent.

Patented Dec. 7, 1920.

Application filed January 26, 1920. Serial No. 354,183.

To all whom it may concern:

Be it known that I, GEORGE E. HARDESTY, a citizen of the United States, and a resident of Folsom, in the county of Union and State 5 of New Mexico, have invented certain new and useful Improvements in Farm-Gates, of which the following is a specification.

My invention relates to an improvement in tilting gates and more particularly to an 10 improvement in tilting gates of the character described and claimed in my prior Patent No. 1,210,797.

An important object of my invention is to provide an improved gate of this character 15 in which the gate proper will be in all of its operative movements positively braced and constrained to travel in the proper path, thereby providing easy, complete and satisfactory operation and preventing distortion or excessive strain being imposed upon 20 the gate proper or any of the associated parts.

Another object is to provide an improved post construction coöperating with the free 25 end of the gate which will insure automatic locking of the gate in closed position.

Another object is to provide an improved rock arm or swing especially adapted to be associated and coöperated with the other 30 elements of a gate of this character.

Another object is to provide a gate of 35 this character of strong and durable construction, easy and reliable in operation and comparatively inexpensive to manufacture.

Other objects and advantages reside in the certain novel features of construction, operation and combination of parts as will become apparent as the description proceeds, 40 reference being made to the accompanying drawings, in which—

Figure 1 is a side elevation of my improved gate showing the gate in closed position;

45 Fig. 2 is a plan view;

Fig. 3 is a side elevation showing the gate in open position;

Fig. 4 is a front elevation of my improved post adapted to coöperate with the free end 50 of the gate;

Fig. 5 is a detail view in side elevation of the truss brace for the gate; and

Fig. 6 is a detail view in plan of the rock arm or swing.

55 Referring to the drawings it will be seen that my invention contemplates a gate in-

dicated generally at 10 and including frame members 11 and horizontal rails 12 secured to said frame members. The rear end of the gate is pivoted between the posts 13 by a 60 pivot 14. The free end of the gate is adapted, in closed position to coöperate with the post 15 which consists of spaced uprights 16 connected at their upper ends by a block 17. Plates 18 are secured to the side of the 65 uprights 16 adjacent the free ends of the gate and have their upper edge curved outwardly and upwardly as shown at 19. As shown in the drawing the inner edges of the plates 18 are spaced and receive between 70 then the free end of the gate. A spring-actuated sliding locking pin or bolt 20 is carried by the gate and coöperates with the under side of the block 17 to maintain the gate in closed position. The plates 18 prevent lateral movement of the gate.

To the rear of the gate and arranged one upon each side thereof are posts 21. A rock arm or swing is pivoted at its upper end between the posts 21, as shown at 22 and is 80 pivoted adjacent its lower end to a lever 27 to be hereinafter more fully described. A rock arm consists of spaced bars 23 which are maintained in spaced relation by spacing sleeves 24, mounted on the pivot shaft 85 25 which extends through the spacing bars as well as through the spacing sleeves, and suitable washers are provided between the end of each spacing sleeve and the adjacent surfaces of the corresponding bar. The upper pivoted shaft 25 is extended at each end thereof beyond the bars 23, and these extensions are journaled in suitable bearings 22 provided therefor in the posts 21. The lower end of the rock arm is pivoted to 95 the lever directly by the spacing sleeve of the lower end of the rock arm which is journaled in a suitable bearing 28 in the lever intermediate its ends. The bars of the rock arm are prevented from separating 100 laterally by upper and lower bolts and nuts 26. The lever 27 also consists of spaced bars, and the lower end of the lever receives between its spaced bars one of the frame members 11 of the gate being pivotally secured as at 29 to this frame member. The outer end of the lever is weighted, as shown at 30.

On each side of the gate and preferably alined with the pivot thereof are provided 110 posts 31. Horizontal extensions 32 are provided upon the posts 21 and 31 and are

braced as at 32'. To the lowermost face of each of these extensions is connected a pulley 33, through which gate-operating cables 34 pass. One end of each of the cables is 5 connected to the spring bolt 20 of the gate and is guided therefrom through a suitable guide opening, or the like; 11' upon the upper end of one of the frame members 11, thence through the pulleys 33 and then 10 hang from these pulleys within convenient reach of persons desiring to operate the gate.

An important feature of the present invention resides in the means provided for 15 bracing the gate and constraining the same to motion in the proper path during all of its operative movements. This means includes a post 35 lying between one of the posts 13 and one of the posts 31 and alined 20 with the posts 13 to which the gate is pivoted. This post is provided with pivots 36 and 37 which carry, respectively, the arms 38 and 39 of a V-shaped brace. The outer ends of the arms 38 and 39 are pivotally 25 connected to one of the frame members 11 of the gate as shown at 38' and 39', respectively. The brace arms, together with the frame member of the gate, constitute a truss, and, like all other trusses, the angular 30 relation between its members can not be changed, except, of course, when one of the members is ruptured. The gate is not only positively guided and braced in its movement with respect to the other structures, 35 but is, in itself, made inherently of greater strength and rigidity. Moreover, the post 35 carrying the V-shaped brace being spaced from the post 13 carrying the gate and alined therewith, the V-shaped brace itself 40 constitutes one member of another truss of which the gate is the second member and the posts 13 and 35 (being maintained in unchanging and stationary relation with each other by reason of being set in the 45 ground) are the third member. This last named truss is effective also both longitudinally and vertically to the end of strength, rigidity, and proper operative movements of the gate.

50 In practice, the gate being closed, when a slight pull is exerted upon the cable 22 the spring bolt is withdrawn from engagement beneath the locks 16 when the gate is swung

upwardly, influenced by the weight 30. The arrangement is such that the weight in the 55 final opening movements resists shocks or jars to the gate. To clear the gate when it is in open position a pull is exerted upon the cable 24 and the gate swings easily toward its closed position, the weight 30 acting to 60 influence the gate in the same manner as heretofore. By virtue of the construction of the posts 15 receiving the free end of the gate, the bracing action applied to the gate and the structure of the lever 27 of the rock 65 arm 23, the gate seeks its proper position easily and without manual guidance, and this, irrespective of the influence of the wind or of other forces, tends to throw the gate to position laterally beyond the spaces 70 between the uprights 16.

I claim:

1. In a device of the character described, in combination, a gate pivoted horizontally, means for tilting the gate from horizontal 75 closed position to vertical open position, means for maintaining the gate in closed position, and means for bracing the gate in all of its operative movements consisting of a V-shaped brace having its apex pivoted in 80 alinement with and spaced from the pivot of said gate and having the outer end of each of its arms pivotally secured to said gate for forming with said gate a truss effective both horizontally and vertically, all as 85 and for the purposes set forth.

2. In a device of the character described, in combination, a gate pivoted horizontally, means for tilting the gate from horizontal closed position to vertical open position, including a pair of posts, a lever consisting of spaced bars having one end embracing said gate and having a weight at its opposite end, and a rock arm consisting of spaced 90 bars, a spacing sleeve for said bars, a pivot 95 shaft extending through said spacing sleeve by which the upper end of said rock arm is pivoted to the posts and a second pivot shaft by which the lower end of said rock arm which embraces the lever is pivoted to 100 the lever intermediate its ends, and means for bracing said gate in all of its operative movements, all as and for the purposes set forth.

GEO. E. HARDESTY.
